UNITED STATES PATENT OFFICE.

EDGAR A. GILLINDER, OF PHILADELPHIA, PENNSYLVANIA.

DESIGN FOR AN ILLUMINATING-LENS.

51,412.

Specification for Design.

Patented Oct. 23, 1917.

Application filed January 2, 1917. Serial No. 140,328. Term of patent 3½ years.

To all whom it may concern:

Be it known that I, EDGAR A. GILLINDER, a citizen of the United States, residing in the city and county of Philadelphia, State of Pennsylvania, have invented a new, original, and ornamental Design for Illuminating-Lenses, of which the following is a specification, reference being had to the accompanying drawing, forming part thereof.

Figure 1 is a face view of an illuminating lens showing my new design.

Fig. 2 is a diametrical section thereof.

I claim:

The ornamental design for an illuminating lens, as shown.

EDGAR A. GILLINDER.
